US0D1072050S

(12) **United States Design Patent** (10) **Patent No.:** **US D1,072,050 S**
(45) **Date of Patent:** **** Apr. 22, 2025**

(54) **LABEL**

(71) Applicant: **Eli Lilly and Company**, Indianapolis, IN (US)

(72) Inventors: **Fernando Ludwig Fernandez Marin**, Maplewood, NJ (US); **Frank N. Hockmuller**, Noblesville, IN (US); **Yuchen Liu**, Flushing, NY (US); **Ross Stephen Merkel**, Fishers, IN (US); **Joseph Vito Primiani**, Astoria, NY (US); **J Geoffrey Swope**, Indianapolis, IN (US)

(73) Assignee: **ELI LILLY AND COMPANY**, Indianapolis, IN (US)

(**) Term: **15 Years**

(21) Appl. No.: **29/838,534**

(22) Filed: **May 13, 2022**

(51) LOC (15) Cl. **19-08**

(52) U.S. Cl.

USPC **D20/27; D20/22**

CLAIM

The ornamental design for a label, as shown and described.

DESCRIPTION

The patent or application file contains at least one drawing executed in color. Copies of this patent or patent application publication with color drawings will be provided by the Office upon request and payment of the necessary fee.

FIG. 1 is a front view of a first embodiment of a label; FIG. 2 is a front view of a second embodiment of a label; FIG. 3 is a front view of a third embodiment of a label; FIG. 4 is a front view of a fourth embodiment of a label; FIG. 5 is a front view of a fifth embodiment of a label; and, FIG. 6 is a front view of a sixth embodiment of a label. The grayscale shading represents a contrast in appearance. All broken lines show portions of the label and do not form part of the claimed design.
